UNITED STATES PATENT OFFICE.

GEORGE T. PARRY, OF PHILADELPHIA, PENNSYLVANIA.

SIGNAL-LIGHT.

SPECIFICATION forming part of Letters Patent No. 448,069, dated March 10, 1891.

Application filed October 6, 1890. Serial No. 367,260. (No model.)

To all whom it may concern:

Be it known that I, GEORGE T. PARRY, a citizen of the United States, residing at Philadelphia, in the county of Philadelphia and 5 State of Pennsylvania, have invented certain new and useful Improvements in Reflecting Marine Signal-Lights; and I do hereby declare the following to be a full, clear, and exact description of the invention, such as 10 will enable others skilled in the art to which it appertains to make and use the same.

My invention consists in a novel combination, with the respective ordinary starboard and larboard red and green marine signal-lights, of 15 novel signal-light-reflecting means, as herein-after described, arranged at a considerable but suitable distance from and in rear of the said lights, whereby the rays or beams of the said lights are conveyed therefrom longitudinally 20 a proper distance backward, and then reflected upon appropriately-colored glasses at right angles to the longitudinal axis of the vessel carrying said lights and said signal-glasses, thus showing at the front the proper 25 illuminated light-signal, and also at the side properly-illuminated light-signals, the said front and side signals being visible to persons on one vessel when the other vessel is moving or crossing directly across the bow of their 30 vessel.

It also consists in certain novel details of construction of the reflected-light signals, whereby the reflected light is confined, and thus a more powerful reflected-light signal 35 obtained.

The objects of my invention are, first, to preserve the integrity of the ordinary main marine signal-lights and prevent them and the reflected light derived therefrom and 40 used for illuminating the reflected-light signal-glasses from blending, and thereby misleading those in charge of marine vessels so as to endanger life and property, and, second, to avoid the necessity of employing two independent lamps and the consequent expense 45 and labor of keeping the additional set of lamps in proper order.

It has been desirable for a long time to have the head-lights of a vessel so arranged 50 as to show to a certainty if one vessel is coming toward another in a slanting direction or crossing directly across her bow. The pres-

ent system of red and green light is universal, although it has been decided by high authority to be defective and uncertain, and while 55 this is so the same authority has announced that the employment or use of two additional or separate lamps would be too troublesome and expensive and liable to be neglected, and therefore less safety insured than if the 60 present plan is adhered to. To remedy the acknowledged defect and to meet the objection to the use of two separate lamps on each side of the vessel and insure a vessel's safety 65 at night and perfect the present system without the additional expense and trouble above mentioned, I have devised the following means:

In the accompanying drawings, Figure 1 is a top view of a marine vessel provided with 70 my invention, the latter shown with the top coverings removed. Fig. 2 is a horizontal section of one of my improved reflecting signal-lights. Fig. 3 is a top view of a complete reflecting signal-light. Fig. 4 is a vertical 75 central longitudinal section of the rear portion of the same, the front portion being broken away. Fig. 5 is a vertical section in the line xx of Fig. 3.

The letter A in the drawings represents a 80 marine vessel of any known construction; B, a front box containing the lamp D; and C, a rear box containing the reflected-light signal-glasses. The front box B consists of a bottom b , a side wall b' , and an end wall b^2 . In 85 the corner formed by the three parts b b' b^2 the lamp D is placed, the same serving as the front light. In line with the flame of the lamp a hole b^3 is provided in the end wall b^2 , through which light from the lamp enters a 90 tube c^3 placed within the box C. The box C is fastened by means of screw-bolts c to the end wall b^2 of the box B, and the tube c^3 , of preferably opaque material, is fastened to the front wall of said box and extended back, 95 preferably in flaring form, to a light-reflecting chamber C' at the rear end of said box, being in communication with said chamber. The shape or angle of said flaring tube should answer as nearly as possible the angle of radiation of the light emitted from the lamp D. The length of the tube c^3 may be varied according to the size of the vessel on which the lights are placed; but it will under all cir- 100

circumstances be best to use a rather long tube in order to insure such a distance between the main light derived, the lamp D, and light reflected from said lamp and conducted 5 through the tube c^2 to the reflecting-chamber C' of the box C. This is essential in order that the front and side lights may be very distinctly seen at a great distance without liability of blending. Should the light from the lamp D be passed immediately into a reflecting-chamber, the light at the front and the reflected light at the side would become so soon blended as to produce a very misleading signal. By giving the tube c^2 a flaring form to 10 ward the reflecting-chamber a very effective distribution of the rays of light from the lamp D is secured, as will be presently seen. Opposite the rear end of the tube c^2 a concave mirror or reflector d is attached to the end 15 wall c^3 of the reflecting-chamber C' of the box C in an inclined position, so as to receive the diffused light emanating from the lamp D and passing through the flaring tube c^2 and throw it upon a concave reflector d' , attached to the 20 inner side wall c^4 of the reflecting-chamber of the box C. The reflector d' throws the light through a colored glass d^2 , suitably secured in the front portion of the reflecting-chamber of the box C, as shown. The glass 25 d^2 is best when made round and set in a plate painted black, as by this construction there will be less blending of the front and side lights.

Extending from the reflecting-chamber C' 30 of the box C are three guards c^5 c^5 c^6 for the purpose of preventing the upward, backward, and forward dissipation of the reflected light passing through the glass d^2 . The guards c^5 are at the sides of the glass and prevent lateral spreading of the light, while the guard c^6 35 is above the said glass and prevents the upward spreading of the light. The color of the glass d^2 is the same as that of the lamp D, so that when the broadside of a vessel is exposed to view two lights of the same color 40 are visible.

When only one colored light is seen, the vessel forms an acute angle with the line of vision and is moving obliquely toward the observer. This latter position of the vessel has heretofore been the cause of many accidents, because in dark nights it has been mistaken for the right-angular position, and thus caused the mariner to pursue his own course too long 50 and rendered a collision unavoidable. The same mistakes may occur when the reflected light is placed close to the lamp D in front of it, because at a more or less distance the two lights will blend and appear as one to the observer, and although this blending may cease as the distance diminishes, at the same time the chances for correction are lessened to the same extent, which is especially the case with steamers and fast-sailing vessels.

65 While I prevent the reflected light from spreading laterally by means of the guard c^5

c^5 and an upward spreading by the very short guard c^6 of the reflected light, I at the same time by using no guard at the bottom insure that the light shall not be hidden from observers when the vessel is rolling in a storm. The guards c^5 c^5 may therefore be made longer than represented, but the guard c^6 should be about as narrow as shown.

In using one lamp for the main light and 75 the reflected signal-light the duties of the attendant are lessened, and I insure a uniform intensity of the two lights, which is not so perfectly accomplished with two independent lamps, one for the front and the other for the 80 side.

From the foregoing description it will be seen that by the adoption of my invention the present system of using and interpreting marine signal-lights is in no way interfered with, 85 and no new rules will have to be laid down for the use and interpretation of signal-lights constructed in accordance therewith, for the reason that the functions of the reflected lights are strictly co-operative with the main or front 90 signal-lights, the latter facilitating the observation of the same.

What I claim as my invention is—

1. In marine signals, the box B, having a signal-lamp D, in combination with the box C, 95 comprising a conducting-tube c^2 , connecting the signal-lamp box with the reflecting-chamber, a reflecting-chamber C', reflecting means, and a colored signal-glass, substantially as described.

2. In marine signals, in combination, the lamp D, giving a colored light in a forward and sidewise direction, the reflectors d d' , reflecting-chamber C', having a signal-glass d^2 , and a tube c^2 , connecting the signal-lamp with 105 the reflecting-chamber and forming a communication between the lamp-box and the reflector-chamber C', of the box C, the said signal-glass d^2 giving a light-signal in a lateral direction and of the same color as the signal 110 of lamp D, substantially as described.

3. In marine signals, in combination, a signal-lamp connected by a tube with a reflecting-chamber and giving a colored light in a rear, forward, and sidewise direction, a reflected light of the same color at a distance 115 from the same, and guards for preventing the reflected light from spreading laterally unduly, substantially as described.

4. In a marine signal-light, the combination 120 of the box B, lamp D, box C, having a reflecting-chamber C', a flaring tube c^2 , and suitable reflecting means arranged within the reflecting-chamber in proper relation to the flaring end of said tube, substantially as described.

In testimony whereof I hereunto affix my signature in presence of two witnesses.

GEORGE T. PARRY.
